UNITED STATES PATENT OFFICE.

HARRY F. THOMPSON, OF STRATFORD, NEW YORK.

ROAD-BUILDING MACHINE.

Application filed March 8, 1927. Serial No. 173,782.

This invention relates to a road building machine, and has for its object the provision of a device which is adapted to remove a predetermined depth of the road in such a manner that a substantially flat surface will be had for the application of other coatings.

A further object of the invention is the provision of a machine adapted to be operated on the steel forms ordinarily employed in the construction of roads for producing a fine grading and in which the surface of the roadbed after the usual coarse grading by power shovel is planed.

A further object of the invention is the provision of a device for producing a fine grading or planing of a roadbed preliminary to its treatment with surface coatings and in which the planing or grading element is movable transversely of the roadbed while the device itself is movable longitudinally on the tops of steel forms ordinarily set by the engineers in constructing a roadbed, the gradings which have been removed being discharged upon either side of the roadbed for filling up the spaces exteriorly of the steel forms.

This invention will be best understood from a consideration of the following detailed description in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a side view in elevation of the device constructed in accordance with the principles of my invention.

Figure 2 is a plan view of the same.

Figure 3 is a vertical longitudinal section, and

Figure 4 is an end view of the planer.

Referring to the drawings, 10 designates a pair of steel rails which form a part of the usual engineer's construction in building roads and for determining the longitudinal edges of the roadbed when the concrete or other plastic materials are employed in the construction. In the first instance a heavy power grading machine is employed for removing the upper surface or crust and it is necessary after this operation to remove a portion of the roadbed to a certain depth for

the application of the various surfacing coats. This removal is usually accomplished by manual labor, making the production of a road expensive. The device forming the subject matter of the present invention is adapted to move over that portion of the roadbed, designated by the numeral 11, in a rapid and economical manner.

The device consists essentially of a frame which includes generally a pair of I beams 12 and such transverse bars as may be required to provide for a rigid frame and for supporting the various elements for normally removing the soil 11 for operating the planer 65 or grading device. A pair of transverse bars 13 and 14 are secured to the longitudinal I beams 12, respectively, by means of plates 15 and 16. A second pair of spaced bars 17 and 18 are secured to the longitudinal 70 beams 12.

Axles 21 and 22 are respectively carried in bearings 23 carried by the underface of the beams 12 and on which are rotatably mounted respectively pairs of wheels 24 and 25. 75 Wheels 24 are rigidly connected to the axle 21 as shown at 26. A shaft 27 is mounted in parallel relation with respect to the axle 21 and is provided with a gear 28 in mesh with a gear 29 rigid with the axle 21. On the other end of a shaft 27 is mounted a sprocket 30 driven by a chain 31 which in turn is driven by a sprocket 32 on a shaft 33. This shaft is caused to be revolved by means of a pair of intermeshing gears 34 and 35, the gear 34 being 80 rigid with a square portion 36 of the shaft 33 while gear 35 is rigid with a shaft 37. The shaft 37 is mounted in a bearing 38 at the outer end of a bracket 39 secured to a standard 85 40 rising from one of the longitudinal I-beams 12. A bracket 41 secured to the standard 40 is provided with a bearing in which is mounted the shaft 33 at one end. A second standard 42 carries a bracket 43 having a bearing 44 on the shaft 33.

A gear 45 rigid with shaft 37 is in mesh with a gear 46 rigid with a shaft 47. This shaft extends longitudinally of the frame and to one side of the frame and is mounted in bearings formed at the ends of brackets 48. 105 One bracket is rigidly secured to one end of the beam 17 while the second bracket is rigidly secured to one end of the beam 13. A gear 49 on one end of the shaft 47 meshes with a gear 50 rigid with a shaft 51. The 110 shaft 51 is directly driven by an engine 52 carried by the transverse I-beams 13 and 14.

As shown more particularly in Figs. 1 and 2 a pair of standards 40 are carried by the I-beams 12 while the other I-beam likewise carries a pair of standards 42. These beams are connected together at their upper ends, as shown at 53, and are braced by diagonally disposed bars 54 extending from the upper end of the standards and secured at their lower ends to the I-beams 12. A bracket 55 is secured to each brace bar 54 to which is connected an I-beam 56 running transversely of the frame and disposed in the plane which is at an angle to the vertical. A carriage 57 is provided with a roller 58 engaging one face of the beam 56 while a roller 59 engages the opposite face. The flanges at the upper end of the beam provide means for maintaining the carriage in operative relation with said beam. This carriage is movable transversely of the frame and longitudinally of the I-beam 56. The carriage is provided with a hook 60 adapted to receive one end of a chain 61. The other end of the chain is secured to the lower end, as shown at 62, to an elevator, generally designated by the numeral 63. The lower end of the elevator is thus supported by the chain 61. This elevator consists of a pair of bars 64 and 65 connected together at their opposite ends and having a sprocket 66 rotatably mounted on an axle 67 carried by the lower end of the space bars 64 and 65. The upper end of the elevator is provided with a sprocket 67^a having a sliding connection with the squared portion 36 of the shaft 33 and is caused to be revolved by the rotation of said shaft. A chain 68 is trained on the sprockets 66 and 67^a and is provided with a plurality of buckets 69 carried by the various links of the chain.

10 A cable 70 is connected at 71 to a bar 65 and is trained over a pulley 72 carried in a bracket which is connected to a brace bar 54. This cable is further trained over a pulley 73 and is connected with a drum 74 having a shaft 75 rotatably mounted in a bearing 76 on the beam 13. A crank 77 is connected with the shaft to cause rotation of said shaft and drum. A second cable 78 is connected at 79 to a beam 64 at the opposite side of the elevator 63 and trained over a pulley 80 carried by a bracket 81 which is mounted on a brace rod 54. This cable, like the cable 70, is also similarly trained over a pulley 82 and has its opposite end rigidly secured to the drum 74 but coiled on the drum in a manner which is opposite to the coiling of the cable 70 on the drum so that rotation of the drum will cause unwinding of the cable 70 and winding of the cable 78 and vice versa.

15 Located adjacent the uppermost end of the elevator 63 is a traveling carrier 85 in the form of a belt mounted on drums 86 and 87. The drum 87 is rigid with a shaft 92 and is driven thereby. The drum 86 is idle and mounted on a shaft 88 carried in bearings at

the outer projecting end of brackets 89 which are secured to the I-beams 17 and 18. It will be noted that a pair of brackets 87^a are located upon opposite sides of the drum 87. Adjacent the innermost bracket 87^a is a transmission mechanism 90 having a shifting lever 91 which is adapted to shift the gears in the transmission 90 for causing a reversal of the shaft 92 so that the direction of movement of the belt 85 is reversed. In this manner the belt may be moved to the right or to the left, depending upon the condition of the roadbed and whether it is desired to deposit the materials raised by the elevator at the right or left side of the roadbed. By means of the transmission 90 it will be seen that the shaft 92 may be connected with the shaft 47 for either right or left hand movement of the belt 85.

20 A hood 93 is secured to the spaced beams 64 and 65 by means of brackets and is so positioned relative to the upper end of the elevator 63 that the materials which are raised by the elevator are deposited directly upon the belt 85. A plate 94 connected by means of brackets 95 to the standards 40 and 42 is adapted to aid in directing the materials onto the belt 85.

25 The operation of my device is as follows: It is usual in the construction of roadbeds to place a pair of steel rails in parallel relation on opposite sides of the roadbed in order to more readily maintain the plastic materials which form the center of the roadbed in position. It is also usual to use a power shovel for removing the top surface of the roadbed preliminarily to the application of the cement or asphalt or macadam. However, after the power shovel has been employed it is necessary to remove a predetermined depth of the materials manually. With the present device the manual removal of the materials is eliminated. The wheels 24 and 25 are placed upon the rails 10 and held in a stationary manner. The inner end of the elevator 63 is then lowered until the buckets 69 will penetrate a sufficient depth for the removal of the materials. At this time machine will be moved forwardly along steel forms any distance required then elevator will be raised enough to clear grade machine has covered. Machine will then be reversed upon steel forms and moved rearward to the place where started then crank 77 will be turned moving elevator transversely about the width of the elevator then elevator will be lowered to the required depth and machine moved forwardly again etc. etc. until grade is completed for that section of steel forms then operating will be carried forwardly on the next section of grade to be graded.

30 When it is desired to move the device forwardly or rearwardly the gears (not shown) of a transmission 101 are moved in a well known manner for connecting or disconnect-

ing the shafts 27 and 27^a or for causing a direct drive of the shaft 27 or reverse rotation of said shaft, depending upon whether the device is to be moved forwardly or rearwardly. The shaft 27^a is driven through the chain 31 which in turn is driven by a sprocket 32. A sprocket 30 driven by the chain 31 drives the shaft 27^a.

I claim:—

- 10 1. A device of the character described comprising an open frame, wheels for supporting the frame, a shaft rotatably mounted on the frame, an elevator supported within the open frame and including a bucket equipped chain, a sprocket slidably mounted on the shaft and driven thereby at the upper end of the elevator, the lower end of the elevator projecting through the bottom of the open frame, bars connected to the frame at the sides thereof and located at an angle to the horizontal, an I beam secured to the bars and located in a plane at an angle to the vertical, a carriage embracing opposite faces of the I beam and mounted for longitudinal movement on said beam, a chain connecting the carriage with the lower end of the elevator, and providing means for adjusting the said lower end in various horizontal positions.
- 15 2. A device of the character described comprising an open frame, wheels for supporting the frame, a shaft rotatably mounted on the frame, an elevator supported within the open frame and including a bucket equipped chain, a sprocket slidably mounted on the shaft and driven thereby at the upper end of the elevator, the lower end of the elevator projecting through the bottom of the open frame, bars connected to the frame at the sides thereof and located at an angle to the horizontal, an I beam secured to the bars and located in a plane at an angle to the vertical, a carriage embracing opposite faces of the I beam and mounted for longitudinal movement on said beam, a chain connecting the carriage with the lower end of the elevator, and providing means for adjusting the said lower end in various horizontal positions.
- 20 3. A device of the character described comprising an open frame, wheels for supporting the frame, a shaft rotatably mounted on the frame, an elevator supported within the open frame and including a bucket equipped chain, a sprocket slidably mounted on the shaft and driven thereby at the upper end of the elevator, the lower end of the elevator projecting through the bottom of the open frame, bars connected to the frame at the sides thereof and located at an angle to the horizontal, an I beam secured to the bars and located in a plane at an angle to the vertical, a carriage embracing opposite faces of the I beam and mounted for longitudinal movement on said beam, a chain connecting the carriage with the lower end of the elevator, and providing means for adjusting the said lower end in various horizontal positions.
- 25 4. A device of the character described comprising an open frame, wheels for supporting the frame, a shaft rotatably mounted on the frame, an elevator supported within the open frame and including a bucket equipped chain, a sprocket slidably mounted on the shaft and driven thereby at the upper end of the elevator, the lower end of the elevator projecting through the bottom of the open frame, bars connected to the frame at the sides thereof and located at an angle to the horizontal, an I beam secured to the bars and located in a plane at an angle to the vertical, a carriage embracing opposite faces of the I beam and mounted for longitudinal movement on said beam, a chain connecting the carriage with the lower end of the elevator, and providing means for adjusting the said lower end in various horizontal positions.

2. A device of the character described comprising an open frame, wheels for supporting the frame, a shaft rotatably mounted on the frame, an elevator supported within the open frame and including a bucket equipped chain, a sprocket slidably mounted on the shaft and driven thereby at the upper end of the elevator, the lower end of the elevator projecting through the bottom of the open frame, bars connected to the frame at the sides thereof and located at an angle to the horizontal, an I beam secured to the bars and located in a plane at an angle to the vertical, a carriage embracing opposite faces of the I beam and mounted for longitudinal movement on said beam, a chain connecting the carriage with the lower end of the elevator, and providing means for adjusting the said lower end in various horizontal positions.

HARRY F. THOMPSON.
